UNITED STATES PATENT OFFICE.

ROBERT A. GALLY, OF NEW YORK, N. Y.

DESIGN FOR A CASE OR STAND FOR MECHANICAL MUSICAL INSTRUMENTS.

SPECIFICATION forming part of Design No. 33,394, dated October 16, 1900.

Application filed September 15, 1900. Serial No. 30,182. Term of patent 14 years.

To all whom it may concern:

Be it known that I, ROBERT A. GALLY, residing at New York, (Brooklyn,) in the county of Kings and State of New York, have invented and produced a certain new and useful Design for a Case or Stand for Mechanical Musical Instruments, of which the following is a specification, reference being had therein to the accompanying drawings.

10 The design consists of the shape or configuration of an article of manufacture known as a case or stand for an automatic musical instrument or piano-player and of ornaments or embellishments placed on or attached to said article of manufacture.

15 Figure 1 is a perspective view of the case or stand for an automatic musical instrument or piano-player. Fig. 2 is a front elevation, and Fig. 3 an end elevation, of said case or stand.

20 A indicates the base of the case or stand. This base is substantially rectangular at bottom, but has projecting side columns B at the ends of the rectangular portion, said 25 columns or pillars being shown as square at the bottom, then cylindrical as to the parts C, and again square as to the upper parts D. The end bars E E of the base are horizontal on top for most of their length, concave at 30 the front, and convex at the rear, as shown,

and an ornamental molding F extends along the end bars and columns. The base, between the end bars, shows inclined surfaces G G. The columns are surmounted by ornamental knobs or buttons II.

35

The box or case K is rectangular and partly incloses one side of the upper members of each of the pillars or columns. The box is shown as longer in its front and rear extension than in vertical height and is much 40 longer in the direction of the pillars than in its rearward extension, the box in its rearward extension being an overhang, or at the rear side of the pillars, but still extending to the rear of the pillars a less distance than 45 does the base. The box has ornamental moldings L at the corners, as shown.

Having described my invention, what I claim as new, and desire to secure by Letters Patent, is—

50

The design for a case or stand for automatic musical instruments, as herein shown and described.

In testimony whereof I affix my signature in presence of two witnesses.

ROBERT A. GALLY.
